FIG. 3.

UNITED STATES PATENT OFFICE

ANTHONY G. HORVATH, OF DAYTON, OHIO, ASSIGNOR TO THE DAYTON PUMP AND MFG. CO., OF DAYTON, OHIO, A CORPORATION OF OHIO

ELECTRIC SWITCH

Application filed November 14, 1928. Serial No. 319,419.

My invention relates to electric switches. It is the object of my invention to provide an electric switch which is operated by hydraulic or pneumatic pressure, or other motive power.

It is an object particularly to provide a switch for air compressors and pumping apparatus, in which the state of the pressure in the apparatus will control the switch to open or close it, in order to maintain a predetermined pressure in the system.

It is a further object of my invention to provide a switch having one or more of the following characteristics:

(a) A snap opening of the switch so that it will be immediately opened without arcing.

(b) The locking of the switch in closed position until sufficient power has been stored up in the opening mechanism to insure immediate and positive opening of the switch.

(c) A secondary safety means of positively opening the switch in the event that a dangerous amount of pressure has been accumulated in the system and the primary means of opening the switch has failed to open it.

(d) Means of moving the switch contacts into and out of engagement with each other so that their faces will always be maintained in parallel relationship.

Referring to the drawings:

Figure 1 is an elevation of the switch with the cover, diaphragm and diaphragm chamber in section, showing the switch parts in position about to snap the contacts out of engagement with one another.

Figure 2 is a similar view, showing the mechanism in position to snap the contacts into engagement with one another.

Figure 3 is a similar view, showing the parts in position to snap out when the primary actuating mechanism has failed and the secondary safety mechanism is about to force out the contacts from engagement with one another.

Referring to the drawings in detail, 1 is a sleeve constituting a connecting means for a pressure pipe connected into the system.

The passageway 2 provides the supply line for the diaphragm chamber 3, the top of which is closed by the flexible diaphragm 4. On this diaphragm is mounted a reciprocating plunger, receiving sleeve 5 that reciprocates through the bottom 6 of the switch casing 7. Suitable openings 8 are provided in this casing for the introduction of electric cables that are connected to the stationary and movable contacts of the switch.

The hollow sleeve 5 contains the thrust pin 9 that is journaled through the block 10 on the pivot 11 in the arm 12. This arm 12 is pivoted at 13 and moves about that pivot. The pin 13 is mounted in the side walls of the casing 7.

The righthand end of the arm 12 is pivotally connected at 14 to a pitman 15. This pitman is pivoted at 16 to the guide link 17 at the righthand side of the link. The pitman 15 is also pivoted at 18 to the righthand side of the main actuating lever 19. This lever is pivoted upon the pin 20, which is stationarily mounted in the ears 21 of the casing 7.

The extreme end of the lever 19 supports upon the pivot pin 22 a bell crank consisting of a cam arm 23, having cam surfaces 24 and 25 and a spring arm 26 through which is loosely mounted an adjustable screw link 27, which carries the main actuating spring 28, the lower end of which is hooked over the free end 29 of the lever 12. Adjustments in the tension of this spring are effected by the position of the nut 30 on the adjusting screw 27.

The brackets 31 on the casing 7 support the bar 32 that carries the stationary terminals and contacts 33. Movable contacts 34 are carried upon the transverse spring plate 35, and in turn are connected by the cable 36 on the switch arm 37. This switch arm reciprocates in a straight line, substantially, being guided by the bar 32 and the link 17.

It carries at its lower end a roller 38 that engages with cam surfaces 24 and 25 of the cam arm 23. It is also engaged by the safety guide link 17, which is pivoted on the stationary pin 39 loosely. Such pin is car-

ried in the side walls of the casing 7, but there is a space around this pin so that movement of the safety guide link can take place without engaging the pin.

5 The latch 40 is also pivoted on the pin 39. This latch has a dual function. It normally acts through the detent 41 operating in the notch 42 in the switch arm 37 to hold the switch in closed position until the spring 28 has stored up such energy as to positively 10 and promptly break the contacts upon removal of the detent 41 from the notch 42. It will be noted that this detent is adjustably mounted on the end of the member 40 by 15 means of the set screw 43 working in the slot 44.

It will be further observed that the member 40 is provided with its own detent head and cam surface 45, which constitutes a 20 safety cam surface which is adjusted to trip the latch 41 from its notch 42 in the event that it does not do so, and in the further event that the pressure becomes sufficient to move the roller 46 against the cam surface 45, which will occur if excessive pressures 25 exist in the system and have not been relieved by the breaking of the switch at lower pressures. Such a condition is shown in Figure 3. The latch 40 is pivotally mounted 30 on the safety link 17, and is yieldingly pressed into latching position by the spring 48.

Method of operation

35 Normally, the pressure system will be operating with a power source such as an electric motor controlled by this electric switch, the motor driving apparatus to build up pressure in the system. It is the object 40 of this switch to stop the motor and stop the building up of the pressure when a predetermined amount thereof has been accumulated in the system.

In Figure 1 the parts are shown in this 45 operating condition, just before the roller 46 has engaged the cam surface 47 of the detent 41 to move it out of position from the notch 42. As the diaphragm 4 lifts it moves the sleeve 5 and the pin 9 upwardly 50 so that the righthand side of the lever 12 moves upwardly about the pivot 13, while the lefthand side moves downwardly, storing energy in the spring 28.

The pitman 15, therefore, moves upwardly 55 and carries with it the safety link 17 about its pivot 39. The result of the movement of the pitman 15 is to lift the lever 19 about its pivot 20 and thereby carry the roller 46 to a position where it will engage 60 the cam surface 47 to move the detent 41 out of engagement with the notch 42.

While this is occurring the energy stored in the spring 28 is increasing and the pressure of the cam surface 24 on the roller 38 65 is increasing, it being the object to eventual-

ly cause the cam arm 23, with its cam surfaces, to press the roller 38 to jerk the switch arm and its movable contacts out of engagement with the stationary contacts, due to the energy in the spring 28, which energy 70 is delayed from being expended until the diaphragm shall have moved a predetermined amount, at which time the switch arm will be unlatched by the detent 41, being withdrawn from the notch 42. As soon as 75 the unlatching is effected the spring 28 will cause the cam arm 23, engaging the roller 36, to press the switch arm 37 downward thereby breaking the electrical contact. The positions of the parts for accomplishing 80 this purpose are illustrated in Figure 3. In Figure 1 the parts are shown with the detent 41 just about to be disengaged from the notch 42. After the detent 41 is disengaged from the notch 42 the pressure 85 of the spring 28, acting upon the arm 23 will cause the bar 37 to lower. When the pressure has been relieved the diaphragm will be lowered and the parts will assume again a position similar to that shown in 90 Figure 2, in which the cam arm 23 is shown in a position beneath the roller 38. When the parts are in the position shown in Figure 2 the pressure within the cavity 3 on the diaphragm 4 will cause the righthand end 95 of the lever 12 to be raised and carry with it the link 15 and the lever 19. In moving the lever 19 the pawl arm 23 is forced against the roller 38, due to the action of the spring 28, whereby the contact member 37 100 is again raised and contact is made.

Safety mechanism

In the event that the cam surface 47 has been displaced or worn, and therefore the roller 46 does not engage it, the roller 46 will come in engagement with the cam surface 45 and force the lock out of engagement with the switch arm so that it can be moved to break the contacts of the switches. This occurs, for instance, if the normal pressure should be twenty pounds and the detachment through the roller 46 takes place at thirty-five pounds pressure.

There is an additional safety mechanism in the safety link 17, which also will move downwardly on its lefthand side a sufficient distance to effect the unlatching and detaching of the movable contacts and the switch arm 37 to break the circuit, if the pressure becomes excessive. This is brought about by the unusual amount of movement, under such conditions, of the pitman 15, which will move the lefthand end of the safety link 17 downwardly about the stationary pivot 39 and thereby pull the switch arm 37 downward and its movable contacts out of engagement with the stationary contacts.

Closing operation

The closing operation takes places when the pressure must be built up by the closing of the electric circuit. The parts in Figure 2 are in position about to close. When the pressure has decreased to a point that the diaphragm has returned to the position shown in Figure 2, the cam surface 24, which has been on top of the roller 38, will snap beneath the roller to put the cam surface 25 underneath it, thereby serving through the tension of the spring 28, to force the movable contacts and the safety arm 37 into closed position, whereupon the latch 41 falls in the notch 42 to hold the switch in that position. The cam surface 25 stays beneath the roller 38 until the pressure builds up to the point where the switch must be opened, whereupon the cam surface 24 is snapped into position above the roller to force the switch arm into its outermost position, as shown in Figure 1, where this has occurred and the switch is about to open. The passageway 2 is provided with alternate rings 50 and notched plates 51 having notches 52, the apertures in the rings and the notches slightly overlapping so that increased pressure may be secured with a larger opening without clogging. This permits of a more accurate and flexible mechanism being secured.

I desire to comprehend within my invention such modifications as may be clearly embraced within my claims and the scope of my invention.

Having thus fully described my invention, what I claim is new and desire to secure by Letters Patent, is:

1. In a pressure switch, a pressure-operating diaphragm, a system of levers, a spring operated thereby for storing energy, a cam moved by the spring, a switch arm and roller engaged by the cam, movable contacts on the switch arm, stationary contacts, latch means for holding the switch arm in closed position, means on the system of levers for detaching the latch upon a predetermined amount of energy being accomplished in the spring, a lever of the system of levers connected to the switch arm for positively moving the switch arm in the event the spring and associated mechanism do not, and supplemental unlatching mechanism adapted to unlatch the latch at a higher pressure in the event the normal unlatching means does not operate.

2. In a pressure switch, a pressure-operating means, a lever operated thereby with a stationary pivot, a pitman on one end, a spring on the other, a second lever pivotally mounted on a switch casing, a bell crank pivotally mounted on the end of the second lever having a cam on one arm, means of attaching said spring on the other arm, a

switch arm, movable contacts thereon, stationary contacts, a latch for latching the switch arm in closed position, and means on the second lever for unlatching said latch at a predetermined point.

3. In a pressure switch, a pressure-operating means, a lever operated thereby with a stationary pivot, a pitman on one end, a spring on the other, a second lever pivotally mounted on a switch casing, a bell crank pivotally mounted on the end of the lever having a cam on one arm, means of attaching said spring on the other, a switch arm, movable contacts thereon, stationary contacts, a latch for latching the switch arm in closed position, means on the second lever for unlatching said latch at a predetermined point, and a safety lever loosely pivoted on said casing and pivoted at either end to said pitman and the switch arm, whereby upon a predetermined additional amount of movement due to excess pressure upon the diaphragm the safety lever will positively move the switch arm out of engaging position, said latching means comprising a normally operative latching and unlatching means and an unlatching means operative under abnormal conditions.

4. In a pressure switch, a pressure-operating diaphragm, a system of levers operated thereby, a spring connected thereto for the storage of energy, a cam actuated by the spring, a switch arm, a cam roller thereon, a latch for holding said switch arm in closed position operating in a notch thereof, said latch comprising a latch member, a cam surface thereon for abnormal unlatching operation, an adjustably mounted detent for engaging said notch having a cam for normal unlatching operation, means for adjusting said detent and cam on the latch, and roller means on the system of levers for engaging said respective cams for normal and abnormal unlatching operations of the movable contacts on the switch arm and stationary contacts.

5. In a pressure switch, a pressure-operating diaphragm, a system of levers operated thereby, a spring connected thereto for the storage of energy, a cam actuated by the spring, a switch arm, a cam roller thereon, a latch for holding said switch arm in closed position operating in a notch thereof, said latch comprising a latch member, a cam surface thereon for abnormal unlatching operation, an adjustably mounted detent for engaging said notch having a cam for normal unlatching operation, means for adjusting said detent and cam on the latch, roller means on the system of levers for engaging said respective cams for normal and abnormal unlatching operations of the movable contacts on the switch arm and stationary contacts, and yielding means between said movable contacts and said switch arm.

6. In a pressure switch, a support comprising a pressure passageway in the bottom of a diaphragm chamber, a diaphragm, a casing engaging the margins of the diaphragm and forming the switch and lever supports, a lever actuated by said diaphragm pivoted on the casing, a pitman pivoted at one end of the lever, and a spring at the other, a second lever substantially parallel to the first actuated by the pitman and pivoted on the casing at one end, a bell crank at the other end of the second lever having means to attach the spring to one arm and angular cam surfaces on the other arm, a vertically reciprocating switch arm, a roller thereon for engaging said cam, a safety link pivotally connected at either end to said pitman and said switch arm and loosely pivoted on said casing, a latch carried on said safety link, pivotal yielding means for maintaining said latch normally in latching position, an unlatching cam, and a latching nose on said unlatching means, said nose engaging in a notch in the switch arm, a roller on the second lever for engaging said cam for unlatching the latch, movable contacts on said switch arm, and stationary contacts carried by the casing.

7. In a pressure switch, a support comprising a pressure passageway in the bottom of a diaphragm chamber, a diaphragm, a casing engaging the margins of the diaphragm and forming the switch and lever supports, a lever actuated by said diaphragm pivoted on the casing, a pitman pivoted at one end of the lever and a spring at the other, a second lever substantially parallel to the first actuated by the pitman and pivoted on the casing at one end, a bell crank at the other end of the second lever having means to attach the spring to one arm and angular cam surfaces on the other arm, a vertically reciprocating switch arm, a roller thereon for engaging said cam, a safety link pivotally connected at either end to said pitman and said switch arm and loosely pivoted on said casing, a latch carried on said safety link, pivotal yielding means for maintaining said latch normally in latching position, an unlatching cam, and a latching nose on said unlatching means, said nose engaging in a notch in the switch arm, a roller on the second lever for engaging said cam for unlatching the latch, movable contacts on said switch arm, and stationary contacts carried by the casing, and means for adjusting the position of said cam and said detent on the latching means.

8. In a pressure switch, a support comprising a pressure passageway in the bottom of a diaphragm chamber, a diaphragm, a casing engaging the margins of the diaphragm and forming the switch and lever supports, a lever actuated by said diaphragm pivoted on the casing, a pitman piv-

oted at one end of the lever and a spring at the other, a second lever substantially parallel to the first actuated by the pitman and pivoted on the casing at one end, a bell crank at the other end of the second lever having means to attach the spring to one arm and angular cam surfaces on the other arm, a vertically reciprocating switch arm, a roller thereon for engaging said cam, a safety link pivotally connected at either end to said pitman and said switch arm and loosely pivoted on said casing, a latch carried on said safety link, pivotal yielding means for maintaining said latch normally in latching position, an unlatching cam, and a latching nose on said unlatching means, said nose engaging in a notch in the switch arm, a roller on the second lever for engaging said cam for unlatching the latch, movable contacts on said switch arm, stationary contacts carried by the casing, means for adjusting the position of said cam and said detent on the latching means, and a supplemental safety cam on said latching means.

In testimony whereof, I affix my signature.

ANTHONY G. HORVATH.
